CLAIM

The ornamental design for a support apparatus, as shown and described.

DESCRIPTION

FIG. 1 is a perspective view of an exemplary embodiment of a support apparatus showing our new design;

FIG. 2 is a front view of the support apparatus of FIG. 1;

FIG. 3 is a rear view of the support apparatus of FIG. 1;

FIG. 4 is a left side view of the support apparatus of FIG. 1;

FIG. 5 is a right side view of the support apparatus of FIG. 1;

FIG. 6 is a top plan view of the support apparatus of FIG. 1;

FIG. 7 is a bottom plan view of the support apparatus of FIG. 1;

FIG. 8 is a perspective view of another exemplary embodiment of a support apparatus showing our new design; and,

FIG. 9 is a perspective view of another exemplary embodiment of a support apparatus showing our new design.

All features illustrated as phantom (broken) lines are

expressly disclaimed and form no part of the claimed design.

1 Claim, 9 Drawing Sheets
